COMB

August Anthony Dapolito, Jersey City, N. J., assignor of one-half to Leonard L. Guardino, Jersey City, N. J.

Application July 19, 1944, Serial No. 545,575

5 Claims. (Cl. 132—11)

This invention relates to a comb.

A primary object is the provision of a comb provided with a self-contained comb case which, when the comb is in use, may be contained within the comb structure itself.

Other objects will in part be obvious and in part pointed out hereinafter.

Having reference now to the accompanying drawings wherein there is shown a preferred embodiment of this inventive concept:

Figure 1 is a side elevational view, certain parts thereof being shown in section, of the combination comb of the instant invention.

Figure 2 is a top elevational view of the structure of Figure 1.

Figure 3 is a side elevational view of the device of Figure 1 as viewed from the opposite side.

Figure 4 is an enlarged end elevational view of the structure of Figure 1 as viewed from the left, certain parts thereof being shown in dotted lines.

Figure 5 is an enlarged sectional view taken along the line 5—5 of Figure 1 as viewed in the direction of the arrows.

Figure 6 is a view similar to Figure 5 but showing certain operating parts in a different position of adjustment.

Figure 7 is an enlarged sectional view taken along the line 7—7 of Figure 2 as viewed in the direction of the arrows, and

Figure 8 is an enlarged perspective view of certain of the parts of the device as they appear when removed from the comb structure.

Like reference numerals refer to like parts throughout the several views of the drawings.

Having reference now to the drawings there is generally indicated at 10 a comb structure provided with a body portion 11, large teeth 12 and small teeth 13.

The upper part of the body portion 11 contains an elongated recess 15, extending substantially the entire length of the comb and open at one end. The end of the comb adjacent the open end of recess 15 is cut in the form of a trough 16 (see Figure 7), the side walls 17 of which serve partially to protect the bristles 18 of a brush 19, provided with a back 20. As best shown in Figure 7, back 20 of brush 19 has integral therewith an offset portion 21, disposed at substantially right angles thereto and containing a slotted recess 22 in substantial parallelism with bristles 18. The end 24 of a nail file 25 (see Figure 8) is adapted to fit into slotted recess 22, and be held in position by a rivet 26 passed through a suitable hole 27 drilled through portion 21 of brush 19, the arrangement being such that file 25 is loosely held

in such manner that it may be swivelled about rivet 26 to place the brush and file in various desired positions for convenience in use.

It may here be pointed that bristles 18 of brush

19 are of varying lengths forming a curved brushing surface which closely conforms, when the parts are in assembled position for carrying, to the bottom of recess or channel portion 16, and that file 25 is adapted to be positioned in recess 10 15 in such manner that when the parts are assembled the overall dimensions of the brush, comb and file are substantially identical or negligibly greater than the overall dimensions of the comb structure itself.

15 Body portion 11 also contains a second recess 30, as best shown in Figures 5, 6 and 7, cylindrical in cross section and closed at both ends. Positioned in recess 30 and having its ends journaled in body portion 11 at the ends of the recess is a rod or axle 31, about which is rolled a sheet 32 or strip of cloth or other suitable material, adapted to serve, in a manner to be pointed out hereinafter, as a cover for the teeth 12 and 13 of the comb. Adjacent each end of axle 31 is positioned a spring 25 33, so arranged as normally to urge rotation of axle 31 in a direction to cause sheet 32 to remain in rolled position thereabout (see Figure 7). Recess 30 extends substantially the full length of comb 10 and has, as best shown in Figure 1, a slot 34 extending thereinto for its full length and through which the end of sheet 32 is adapted to project. The outer end of sheet 32 is provided with a plurality of tabs 35 which provide means for readily grasping the sheet to pull the same through the slot 34 into position to cover the teeth of the comb. Each of tabs 35 has a hole 36 therein in which holes are adapted to engage, when the sheet is in covering position, suitable buttons 37 positioned on the body of comb 11 on the side opposite slot 34 (see Figures 5 and 6). A suitable thickening strip 38 is secured along the outer edge of the strip 32 to prevent the end portions or tabs 35 passing through slot 34 to such position where they may not be readily grasped by the user.

45 From the foregoing the use and operation of this construction should be readily understandable. When the user desires to file his nails the end of brush 19 is grasped and nail file 25 removed from recess 15, used, after which the nails 50 may be brushed with brush 19, and the assembly replaced.

When the comb is carried in the pocket, cover sheet 32 is normally positioned about the teeth of the comb and end tabs 35, through recess 30 secured on projecting fasteners 37 to effectively

cover the teeth of the comb and prevent the access of dust or dirt thereto. When it is desired to use the comb, fastening means 36—37 are released and springs 33 cause sheet 32 to assume the rolled position shown in Figure 5 within recess 30. After using the comb tabs 35 are grasped and the sheet returned to covering position and secured.

From the foregoing it will now be seen that there is herein provided a combination comb accomplishing all the objects of this invention, and others, including many advantages of great practical utility.

As many modifications may be made of this inventive concept it is to be understood that all matter hereinbefore set forth or shown in the drawings is to be interpreted merely as illustrative and not in a limiting sense.

I claim:

1. In a device of the character described, a comb body having a cylindrical recess therein and a slot opening into said recess, teeth associated with said comb body, an axle in said recess, a sheet of material adapted to be utilized as a cover for said comb rolled about said axle in said recess, means facilitating unrolling of said sheet through said slot for positioning about the teeth of said comb, means for securing said sheet in unrolled position, and resilient means for urging said sheet to rolled position when said securing means are released.

2. In a device of the character described, a comb body having a cylindrical recess therein and a slot opening into said recess, teeth associated with said comb body, an axle in said recess, a sheet of material adapted to be utilized as a cover for said comb rolled about said axle in said recess, means facilitating unrolling of said sheet through said slot for positioning about the teeth of said comb, means for securing said sheet in unrolled position, and resilient means for urging said sheet to rolled position when said securing means are released, said last-mentioned means comprising springs associated with the ends of said axles.

3. In a device of the character described, a

comb body having a cylindrical recess therein and a slot opening into said recess, teeth associated with said comb body, an axle in said recess, a sheet of material adapted to be utilized as a cover for said comb rolled about said axle in said recess, means facilitating unrolling of said sheet through said slot for positioning about the teeth of said comb, means comprising tabs on the end of said sheet having securing holes therein, and fasteners on the side of said body opposite said slot, for securing said sheet in unrolled position, and resilient means for urging said sheet to rolled position when said securing means are released.

4. In a device of the character described, a comb body having a cylindrical recess therein and a slot opening into said recess, an axle in said recess, a sheet of material adapted to be utilized as a cover for said comb rolled about said axle in said recess, means facilitating unrolling of said sheet through said slot for positioning about the teeth of said comb, means for securing said sheet in unrolled position, resilient means for urging said sheet to rolled position when said securing means are released, and means for precluding the passage of the end portion of said sheet through said slot into said recess.

5. In a device of the character described, a comb body having a cylindrical recess therein and a slot opening into said recess, an axle in said recess, a sheet of material adapted to be utilized as a cover for said comb rolled about said axle in said recess, means facilitating unrolling of said sheet through said slot for positioning about the teeth of said comb, means for securing said sheet in unrolled position, resilient means for urging said sheet to rolled position when said securing means are released, and means for precluding the passage of the end portion of said sheet through said slot into said recess, said last-mentioned means comprising a thickening strip across the outer end of said sheet whereby the thickness of said sheet at that point is greater than the width of said slot.

AUGUST ANTHONY DAPOLITO.
